APPARATUS FOR CLEANING A BOWLING PIN
Herman C. Behrendt, 2312 University, Des Moines, Iowa
Filed Mar. 23, 1960, Ser. No. 17,212
1 Claim. (Cl. 15—21)

This invention relates generally to apparatus for cleaning an article and more specifically to improvement in an apparatus for the cleaning of a bowling pin.

In recent years there has been a large increase of automation instilled into the game of bowling. Not only have there been automatic scoring machines, but there have been installed in almost every bowling alley, automatic pin setting machines. Due to the use of the automatic pin setting machines, there is an increased requirement for a constant change of bowling pins. As is well realized due to the speed-up of the game caused by the use of the automatic pin setters, the bowling pins are in constant use and as such receive more wear and contact with the backstop and the floor member in a much shorter period of time. It has therefore become necessary to provide a quick means for the cleaning of the increased number of bowling pins that are used.

Heretofore it has been necessary to utilize large bulky equipment for the cleaning of the bowling pins. The cleaning apparatus is not only bulky and expensive but the structure of this equipment has been such that the parts are not easily replaced and the maintenance cost is very high.

It is therefore the primary object of this invention to provide a bowling pin cleaning device which is not only compact in size but is so constructed to have replaceable parts to reduce the maintenance cost.

The specific object of this invention is to provide a bowling pin cleaning apparatus which has a rotatable drum in which the bowling pin is inserted coming into contact with a plurality of spring loaded brush members to perform the cleaning operation.

Another object of this invention is to provide an improved bowling pin cleaning apparatus in which the entire surface of a bowling pin will come into contact with rotating, contoured brush members resiliently mounted within the housing to perform the cleaning operation.

A still further object of this invention is to provide an improved bowling pin cleaning apparatus in which the cleaning container is easily removed from the drive motor.

Another object of this invention is to provide a resilient releasable holding means for the end of the cleaning brushes within the cleaning container.

With the foregoing and other objects in view, the invention resides in the following specification and appended claims, certain embodiments and details of construction of which are illustrated in the accompanying drawings, in which:

FIGURE 1 is a perspective view illustrating an operator placing a bowling pin into the bowling pin cleaning apparatus of this invention;

FIGURE 2 is a section view taken along the lines 2—2 of FIGURE 1;

FIGURE 3 is a perspective view illustrating a resilient releasable holding mechanism, for the lower ends of the brush members, mounted on the lower surface of the cleaning container;

FIGURE 4 is a section view taken along the lines 4—4 of FIGURE 1 illustrating the bowling pin fully inserted into the cleaning container with a portion of the bowling pin cut away showing the connection with the bowling pin holding tool;

FIGURE 5 is a plan view of the spring loaded holding tool;

2

FIGURE 6 is a section view taken along the lines 6—6 of FIGURE 5; and

FIGURE 7 is a section view taken along the lines 7—7 of FIGURE 5.

5 Referring now particularly to the drawings, a bowling pin cleaning apparatus of this invention indicated generally at 1, which includes an upper cleaning section 2 which has an outside housing 3. The outside housing 3, being of any suitable non-corrosive metal, is in cylindrical shape and is provided with an opening 4 on its upper surface 5. Referring specifically to FIGURE 4 the upper surface 5 of the container 3 has a contoured surface with the opening 4 being centrally located therein. The periphery of the opening 4 has a rounded lip member 6. The contour of the lip member 6 provides for smooth easy insertion of a bowling pin into the container 3, and also assures no additional scratching or marring of a bowling pin.

Centrally mounted on a lower surface 7 of the container 3 is a connecting sleeve member 8. Sleeve member 8 is secured to the surface 7 by any suitable means, as by welding. The sleeve member 8 has a lower recessed portion 9 which engages a corresponding bearing support secured to the motor housing frame which will be explained later. The sleeve 8 has a central opening 10 of which the upper portion has a slotted opening 11.

A drive shaft 12 extends through the motor frame housing 13 and into the opening 10 of the sleeve 8. The drive shaft 12 has a protruding pin member at one end 30 which engages the slot member 11 of the sleeve 8. This type of connection is referred to in the art as a bayonet type connection and it is easily seen that the upper cleaning housing can be easily removed from the drive shaft.

The frame structure 13 not only provides a housing 35 for a drive motor 14 but also provides a stable base for the bowling pin cleaning apparatus. Centrally mounted on the upper surface of the frame 13 by means of hold-down screws 15 is a protruding bearing support 16. A thrust bearing 17 is secured in the mount 16 through 40 which the drive shaft 12 passes and engages the sleeve 8. The bearing support 16 has its upper portion engaged with the recessed area 9 of the sleeve 8. Thus it is easily seen not only does the invention provide an easy quick disconnect of the cleaning housing 3 from the drive 45 motor frame structure 13, but it also provides a protective shield for the thrust bearing 17 by means of the sleeve 8.

The drive shaft 12 extends in a downwardly direction passing through a thrust bearing 18 which is secured 50 in a bearing mount 19. The mount 19 is secured to the frame structure 13 by a plurality of screw members 20. A pulley member 21 is keyed or secured to the lower end of the drive shaft 12. The pulley 21, being driven by the belt 22, receives its power from a corresponding 55 pulley attached to the drive motor 14. Linear movement of the drive shaft 12 is prevented by a bearing member 23 which is securely held to the lower surface of the frame structure 13.

60 Referring now specifically to FIGURES 2, 3 and 4, a plurality of brush members 24 are resiliently mounted 120° apart within the housing 3. Each of the brush members 24, being of any suitable commercial brush material, has a contoured metal backing plate 25. The metal backing plate 25 has a contour corresponding to that of the bowling pin. Each brush member 24 may be secured to the backing plate 25 by any suitable means and is illustrated in the drawing as being connected by a plurality of pins 26.

65 Referring now specifically to FIGURES 2 and 4, the backing plate 25 is secured to a resilient holding bracket indicated generally by the number 27. The holding 70 bracket 27 is secured to the frame structure 13 by a plurality of screws 28.

bracket 27 has two side members 28 which have slotted openings 29. The side members 28 are secured as by welding to the housing 3 and extend inwardly towards the center of the housing 3. Adapted to slide within or between the members 28 is a plunger 30. The plunger 30 connects or telescopes over a pin member 31 protruding from the metal backing plate 25. The pin 31 is secured to the backing plate 25 by any suitable means such as welding. A compression spring 32 is positioned between the two side plates 28 and behind the plunger 30 whereby one end of the compression spring will be forced against the housing 3 while the other end is acting on the plunger 29. To keep the brush member 24 and plate member 25 from turning or twisting due to the rotary action of the housing 3 the holding bracket 27 has a cotter pin 33 which passes through the slots 29 in the side members 28 and also through an opening 34 in the plunger 30. Thus it is easily seen that through the action of the holding bracket 27 the brush members are urged in an inward direction towards the bowling pin and are held in secured relationship from any torque set-up due to the rotation of the housing 3. The holding bracket 27 is positioned towards the upper end of the housing 3. The advantage of locating the holding brackets 27 in this position will be discussed later.

Referring now specifically to FIGURES 3 and 4, a resilient releasable holding attachment, indicated generally by the numeral 35, for holding a lower tip 36 of the contoured backing plate 25, is secured to the lower or bottom surface of the housing 3. The locking attachment 35 has a bracket 37 through which passes a shaft member 38. The shaft member 38 is urged in an inward direction by a compression spring 39. A cotter pin 40 passing through the shaft 38 prevents the shaft from being urged through the bracket 37. The compression spring 39 has one end pressing against the bracket 37 and the other end pressing against a plate 41 in which the shaft 38 terminates.

Centrally secured to the lower portion or surface of the housing 3 is a tip brush bracket 44. The brush bracket 44 being hexagon in shape provides a plurality of side wall members 45 alternate ones of which are provided with terminal outwardly extended and upright lips 60 spaced apart to receive the plate 41 therebetween. The upper ends 61 of the lips 60 are flared or bent away from each other, while the upper surface 62 of the plate 41 is tapered or inclined downwardly toward the bracket 44 which is of any suitable corrosive resistant metal, and fixedly secured to the bottom wall of container 3. Centrally mounted on the bracket 44 in order to come in contact with the uppermost point of the bowling pin is a brush 46. The brush 46 is secured to the bracket 44 by any suitable means, illustrated in the drawings as being a friction fit pin 47.

Referring specifically to FIGURE 4 now, the action of the holding attachment 35 forces the tip or lower portion 36 of the backing plate 25 into contact with a side 45 of the bracket 44, at a position between a pair of lips 60. It is obvious that the holding of the tip portion 36 between the lips 60 and plate 41 will urge the complete brush member 24 and backing plate 25 in an inward direction in conjunction with the action of the holding bracket 27 when the bowling pin is removed. The brushes 24 maintain their position upon removal of the bowling pin due to the over center position of the holding bracket 27 in which the weight of the assembly will keep the pin member 31 within the plunger 30.

It is obvious that to remove the brushes 24 all that is required is to move the brush towards the center of the container 3 until the pin 31 clears the recess in the plunger 30 and then pull in an upward direction to disengage the holding attachment 35. Replacement is as easily made by inserting the tip portion 36 of the backing plate 25 into the holding or locking attachment 35, the bent ends 61 of the lips 60, and the inclined surface 62 of the plate 41 acting as guides, and then placing the pin 31 into

the recess of plunger 30. Stated otherwise, the lips 60, a side 45 of the bracket 44 and a corresponding plate 41 form an expansible socket for receiving the lower end tip portion 36 of a backing plate 25.

Referring now to FIGURES 2 and 4, a plurality of stationary guard members 48 are positioned 120° apart between adjacent brush members. Each guard member, being permanently secured to the inner surface of the container 3, has a contoured surface corresponding to that of the larger portion of the bowling pin. The stationary guards 48 function to guide a bowling pin as the pin is inserted, within the opening 4 to a fully extended position within the circle or ring formed by the brushes 24. As is apparent upon entrance of the first portion of the bowling pin within the container 3 the torque action of the brushes will have a tendency to force the tip or head of the bowling pin to a position between a pair of adjacent brushes, but as the tip tries to move to such position it will come into contact with a stationary guard member 48 and be guided toward the center of the housing 3.

Located near the lower portion of the container 3 is an outlet 49 sealed by a removable plug 50. This provides an adequate means for draining the container 3 of any cleaning liquids therein.

In utilizing this bowling pin cleaning apparatus the container 3 is first filled with a detergent or cleaning liquid. After the proper solution is in the container 3 and the drive motor has the cleaning container in a spinning condition, the bowling pin is inserted through the opening 4 while being held by a special plier like tool 51 which is to be explained later. It is quite obvious that through the action of the spring operated brush members 24 and the tip brush member 46, the complete surface of the bowling pin will be in constant contact with the brushes and the cleaning solution.

The plier like tool 51 is used to hold the bowling pin in a secured position while the cleaning operation is taking place and includes a pair of handle members 54 integrally formed at one of their ends with tong or gripping members 52. A spring 53, arranged in compression between the handles 54 urges the gripping members 52 to a closed position. As best shown in FIGURE 6 each member 52 is of a semi-circular shape in transverse cross section, and in closed position form a substantially cylindrical unit of a size to be freely received within the usual cavity 67 formed centrally in the base of a bowling pin.

The handle members 54, pivot about a pivot pin 55 having one end 64 threaded into one of the handle members 54, and its headed end 65 loosely received within a tapered hole 66 formed in the other handle member 54. The loose fit about the pin 55 is provided so that one handle member is free to move relative to the other. Positioned forwardly of the pivot pin 55 is a guide pin 56 utilized to keep the gripping or tong members 52 in longitudinal alignment. It is easily seen that it is only necessary for the operator to insert the tip or gripping portions 52 of the tool 51 into the bottom opening 67 of the bowling pin and then by pressing together the handle members 54 to move the gripping members 52 away from each other into frictional engagement with the side wall of the opening or cavity 67, holding the pin while it is being cleaned by the cleaning apparatus.

While the apparatus of this invention is shown and described with particular reference for the cleaning of bowling pins, it is apparent that many of the features shown may be used in a variety of combinations and with other attachments for cleaning other structures of different contour and that many of the details thereof may be considerably modified without departing materially from the features of the invention as claimed.

What is claimed is:

In a device for cleaning bowling pins having a base section and a reduced neck section, including a rotatable cylindrical container open at the top and having a bot-

tom wall and a side wall, a plurality of brush means each contoured to the shape of a bowling pin and including a back member, said brushes positioned upright within said container in a circumferentially spaced relation concentric with said side wall, with the portion of a brush back member contoured to the neck portion of a pin being lowermost, and the portion thereof contoured to the base section of a pin being uppermost, means corresponding to said brush means for releasably and yieldably receiving the lower end of a corresponding back member against radial and circumferential movement relative to said container, a plurality of side wall supported means corresponding to said brush members and arranged at positions opposite the uppermost portion of a corresponding back member, with each of said side wall supported means including a plunger member extended radially of said container and formed with an axial cavity in the inner end thereof facing a corresponding back member, means for biasing said plunger toward

a corresponding back member, and a projection on a back member receivable within the cavity of a corresponding plunger, with the lowermost end of each back member being releasably held at a position inwardly of the container relative to the inner end of a corresponding plunger, whereby a brush means is removed from within the container by initial disengagement of a pin from a plunger and upward movement of the brush means from a bottom wall supported means.
